CLAIM

The ornamental design for an arrangement of snuff packages in a snuff container, as shown and described.

DESCRIPTION

FIG. 1 is a perspective view of a first embodiment of an arrangement of snuff packages in a snuff container showing our new design;

FIG. 2 is a top plan view thereof;

FIG. 3 is a perspective view of a second embodiment of an arrangement of snuff packages in a snuff container showing our new design; and,

FIG. 4 is a top plan view thereof.

The broken lines in the drawings depict portions of the arrangement of snuff packages in a snuff container that form no part of the claimed design.

1 Claim, 4 Drawing Sheets
